UNITED STATES PATENT OFFICE.

DUNCAN McDONALD, OF MONTREAL, QUEBEC, CANADA.

PASSENGER-CAR.

992,571.

Specification of Letters Patent. Patented May 16, 1911.

Application filed August 9, 1910. Serial No. 576,307.

To all whom it may concern:

Be it known that I, DUNCAN McDONALD, a subject of the King of Great Britain and Ireland, residing in Montreal, Province of 5 Quebec, Dominion of Canada, have invented certain Improvements in Passenger-Cars, of which the following is a specification.

The object of my invention is to construct a car which may be used for train 10 service where two or more cars are coupled together so that the system known as the "pay-as-you-enter" system may be used, that is, separate passageways for the ingress and egress of passengers, the passenger paying his fare on entering the car.

The invention is particularly adapted for use in suburban traffic and on underground and overhead railways, although it can be used in the ordinary train service without 20 departing from the essential features of the invention.

In the accompanying drawing:—Figure 1, is a diagrammatic plan view of a train of passenger cars illustrating my invention; 25 and Fig. 2, is an enlarged sectional plan view of the abutting platforms of two cars.

Referring to Fig. 1, A is the forward car of the train; A' is the middle car and A² is the rear car. These cars are all built 30 exactly alike and are coupled together, forming a three-car train, although it will be understood that any number of cars may be coupled together, as desired.

The body of the car is divided from the 35 platform B by a transverse partition C having, in the present instance, sliding doors e, e' which abut against a central post C'. The platform B is of such a width that it can be divided into two passageways by 40 a rail D or other partition, the passage B' next to the partition C being the egress passageway and the passageway B² being the ingress passageway.

b, b' are series of steps, one series being 45 on one side of the platform and the other series being on the other side of the platform and, in the present instance, the steps are divided by permanent rails E, E'.

The rail D is shaped so that one portion 50 is at right angles to the other, as shown. The rail is adapted to a socket d mounted on the center post C' and it is also supported by a standard d' and is arranged to swing either to align with the rail E, as shown in Fig. 2, or to align with the rail E'.

on the opposite side of the car, according to the direction of movement of the train.

At each side of the car at each end are sliding doors, in the present instance, and these doors may be either arranged to slide 60 on the outside of the car, as shown in the drawing, or in the framework of the car, as desired, according to the design of the car. When the rail D is in the position shown in Fig. 2, then the door F is open so that 65 passengers can enter or leave the car, while the other side of the platform is closed by the door F'.

In order to allow passengers to mount the 70 platform of one car and pass into the car adjoining it, I provide passageways in the vestibule casings I, I' of the platforms of the cars and in order to close these passageways I provide doors i, i' hinged in the present instance and arranged to be moved 75 back against the fixed framework of the vestibule, as clearly shown in the drawings. The vestibule framework may be of any shape desired, according to the type of the 80 car being used, and the doors may be either divided, as shown, or may be of the sliding type without departing from the essential features of my invention; the doors leading from one car to another being under the control of the conductor, as well as the doors 85 leading into the cars from the platform. The conductor by opening only one entrance on one side of the car and closing the entrance on the opposite side of the car and both of the entrances of the adjoining platform of the car to which the first car is 90 coupled can control the entrance into both cars.

While I have shown in the drawing the 95 egress passageway the same width as the ingress passageway, the ingress passageway may be of greater width in some instances than the egress passageway, in order to allow passengers to more quickly board the car. Thus it will be seen that if, for 100 instance, three cars are entrained, as in Fig. 1, x and x' would be the only entrances to the cars and these, together with the passageway x² at the forward end of the car, would be the only exit passageways, so that two 105 conductors and a motorman could handle the train. The passengers would enter through the passageway B² on cars A and A' and passengers could pass into the rear 110 of the cars A, A' or the forward end of car

A². Passengers leaving the car could pass through the several exit passageways B' without interfering with the passengers entering the car. If the cars are run in the opposite direction to that indicated in the drawing, then the doors F are closed and the doors F² opened; the doors F' and F³ remaining closed. The hand rail D is then turned from the position shown in Fig. 2 to that shown by dotted lines in said figure.

While I have shown the platforms inclosed by a casing and doors, it will be understood that railing and gates may be used without departing from the essential features of the invention. In some instances it may be desirable to form a wide passageway in the transverse partition and to dispense with the central post, and when a wide passageway is formed then I prefer to discontinue the rail on the platform some distance from the partition.

I claim:

1. The combination in a passenger car, of a body portion, a platform, a transverse partition dividing the platform from the body portion and having two doorways therein, doors for closing said doorways, a center post separating the two doorways, fixed rails at each side of the platform, a swinging rail extending from the post and adapted to aline with the fixed rail on either

side of the car, doors for closing the platform at either side of the car, a vestibule framing extending from one side of the car to the other, and a passageway in said framing so that a passenger entering a car can pass either into the body of the car or into the body of the adjoining car. 35

2. The combination in a train of passenger cars, each car having a platform at each end, each platform separated from the body of the car by a transverse partition having passageways therein separated by a central post, a fixed rail at each side of each platform separating the platform into ingress and egress passageways, a movable rail alining with the posts and adapted to swing into alinement with the fixed rails on either side of the platform, each platform being inclosed by a vestibule casing, a passageway in the center of each vestibule casing, doors for closing the said passageways, and doors for closing the ingress and egress openings to and from the platform. 40 45 50

In testimony whereof, I have signed my name to this specification, in the presence of two subscribing witnesses. 55

DUNCAN McDONALD.
